UNITED STATES PATENT OFFICE.

VINTON E. SISSON, OF CHICAGO, ILLINOIS, ASSIGNEE TO WALTER P. MURPHY, OF CHICAGO, ILLINOIS.

Sheet-Metal End Structure for Railway-Cars.

1,271,234.

Specification of Letters Patent.

Patented July 2, 1918.

Continuation of application Serial No. 775,294, filed June 23, 1913. This application filed January 22, 1915. Serial No. 3,781.

To all whom it may concern:

Be it known that I, VINTON E. Sisson, a citizen of the United States, residing at Chicago, in the county of Cook and State of Illinois, have invented certain new and useful Improvements in Sheet-Metal End Structures for Railway-Cars, of which the following is a specification.

My invention relates to the construction of railway cars and more particularly to metal end structures for railway cars made up of one or more sheet steel plates or panels formed with reinforcing and stiffening corrugations. It is well known that the end walls of railway box cars are more likely to be broken or otherwise injured than the side walls. This is due to the inertia thrusts and pressures caused by the shifting of the cargoes when the train starts and stops. These thrusts may be local, tending to perforate the end in some particular spot as, for example, when a piece of piping or lumber shifts lengthwise against the end wall of the car; or there may be general tending to break out the end wall as a whole or tear it away from the framing. For the purpose, therefore, of greater strength and durability, car ends have of late been constructed of sheet metal corrugated or formed with ribs calculated to give the desired strength and rigidity.

One of the principal objects of my invention is to provide a corrugated sheet metal end structure for railway cars in which the corrugations have a configuration and arrangement that impart to the structure a maximum capacity for resisting cargo thrusts, both local and general, with a minimum weight of metal. It is important that structures of this sort should be as light as is possible, consistent with strength and durability, both for reasons of economy in manufacturing cost and also so that they will add as little as may be to the weight of the car.

The invention has for further objects such other new and improved constructions and arrangements in sheet metal car ends as will be hereinafter described and claimed.

This application is a continuation of my application Serial No. 775,294, filed June 23, 1913; certain typical forms of the invention herein disclosed being originally shown and described in said application.

The invention is illustrated, in certain preferred constructions, in the accompanying drawings wherein—

Figure 1 is an end elevation of the superstructure of a box car provided with a sheet metal end wall constructed in accordance with my invention.

Fig. 2 is a sectional view on line 2—2 of Fig. 1.

Fig. 3 is a fragmentary sectional plan on line 3—3 of Fig. 1.

Fig. 4 is a view, in elevation, of a car end constructed according to the general principles of my invention but having the strengthening corrugations running horizontally instead of vertically.

Fig. 5 is a sectional view on line 5—5 of Fig. 4.

Fig. 6 is a fragmentary view, in perspective, of the upper panel in the structure shown in the preceding two figures.

Fig. 7 is a sectional view taken on line 7—7 of Fig. 6.

Fig. 8 is a fragmentary vertical sectional view illustrating how the panels may be reversed so that the corrugations will project outwardly from the marginal portions of the panels instead of inwardly.

Fig. 9 is a view of one of the panels in process of manufacture, that is, after the corrugations have been pressed out before the sheet has been trimmed.

Figs. 10 and 11 illustrate the method of forming the central corrugated portions of the panels, these figures being sectional views at right angles to each other through the pressing dies, the panel being shown between the dies in the shape which it takes at the end of the pressing operation.

Like characters of reference designate like parts in the several figures of the drawings.

Referring first to Figs. 1 to 3 inclusive, 25 designates one of the end plates of a railway box car, 26 the end sill, 27 the flooring of the car, 28 the corner posts and 29 the side girths or belt rails.

The end structure in this form of the invention consists of an upper panel 30 secured to the end plate 25 by bolts 31, one of which preferably passes through the end facia plate 32; and a lower panel 33, the upper edge of which underlaps the lower edge of the upper panel and is secured thereto preferably by a double line of rivets 34.

Both panels are preferably formed with vertical flanges 35 secured to the corner posts 28 by bolts 36. The lower panel is attached to the end sill 26 by any suitable attaching devices, such as lag screws 37, and is, furthermore, riveted to an angle bar 38, the other part of which extends under the flooring 27 and rests upon the end sill 26, being secured to the latter by bolts 39. The end 10 structure is preferably anchored to the belt rails 29 by anchoring devices 40.

The panels 30 and 33 comprise, in each case, a central corrugated portion surrounded by a flat marginal portion. The central 15 corrugated or stiffened portion of the plate is formed by a series of outwardly pressed vertical corrugations 41; these corrugations being preferably of uniform width and depth, for the greater part of their length at 20 least, and merging directly one into the other. These corrugations provide a series of contiguous rib-like formations of substantially equal width projecting alternately in opposite directions from each other, the inwardly projecting formations being designated 41^a. In cross sectional configuration this portion of the panel describes preferably an ogee curve. The configuration of the corrugated or stiffened portion of the 25 panel gives the panel a maximum amount of strength and rigidity resisting deflection, since the corrugations, in effect, constitute beams, and when thus located side by side a pressure brought to bear against one of these 30 beams has to be capable of producing distortion of the adjacent beams before the panel as a whole can suffer strain. The arrangement in this regard is far superior, for the particular purposes for which the panels are 35 designed, to one in which ribs are pressed in a sheet of metal with comparatively wide spaces between them. Furthermore, the panels as preferably constructed present curved or undulated surfaces to the load in 40 the car which tend to deflect the impact of relatively small, heavy articles which would be likely to puncture a flat surface. The outturned corrugations 41 are preferably formed with tapered or semi-conical terminal 45 portions 42 which merge into the upper and lower marginal portions of the panels. The corrugations are preferably formed in this way for reasons which will be hereinafter explained in connection with the operation 50 of manufacturing the panels. All of the corrugations terminate within the edges of the panels, thus providing the upper and lower marginal portions above referred to. The purpose of these marginal portions is, 55 first, to stiffen and rigidify the panel as against the tendency to bulge on vertical lines. If the corrugations ran to the edges of the panels, a load upon either of the panels would tend to expand the corrugations and in consequence deflect the end. 60

This tendency is resisted by the flat marginal portions which extend across the panels at opposite ends of the corrugations. The flat marginal portions at top and bottom of the panels and likewise the flat marginal 70 portions at the sides, afford means for securing the end structure to the framing of the car with a weather and grain proof connection. By overlapping the panels at the middle for a considerable distance and connecting them with two lines of rivets, as shown, a girth member or reinforcing band is provided which takes the stresses transmitted to it by the corrugations and carries them to the corner posts of the car. 75

In Figs. 4 to 7 inclusive, I have shown an end structure made up of panels constructed on the same general principles as the panels employed in the car ends previously described, the difference being that the corrugations instead of running vertically extend horizontally across the car from side to side. The panels are designated 49, 50. The upper panel 49 comprises, it will be seen (Fig. 6), a central corrugated portion 51 and a 80 flat marginal portion 52 surrounding the corrugated portion. The corrugated portion is composed of a plurality of parallel inturned corrugations 53 of uniform width and depth, for the greater part of their 85 length, and with pointed or semi-conical terminal portions 54 which die out into the flat margins at the sides of the panels. The corrugations 53 merge one into the other providing in effect a series of oppositely inwardly and outwardly turned rib-like formations the latter being designated 53^a. The panels may be connected in any suitable manner. Inasmuch as the beams, the corrugations 53, 53^a, run horizontally so as to 90 transmit stresses directly to the corner posts of the car, it will ordinarily be sufficient to simply overlap the panels one upon the other and connect them by a single line of rivets 55. 95

In Figs. 9 to 11 I have illustrated the 100 method of forming a panel such as that shown in Fig. 6. It will be obvious that the panels forming the constructions illustrated in Figs. 1 to 3 might be similarly formed.

A sheet of metal 49^a is placed upon a stationary die 56 formed with upwardly projecting ribs 57 and between these ribs with corrugations or recesses 58 which are considerably wider than the ribs. The upper or movable die 59 is formed with recesses 60 115 in which the ribs 57 enter and with rounded projecting ribs 61 adapted to enter the corrugations 58 in the lower die. The ribs 57 and 61 are of uniform height and thickness and in length correspond to the length 120 of the central portions of the corrugations of the finished plate, that is, the length of the corrugations less their pointed ends. When the upper die is brought down upon the sheet of metal on the lower die so as to 125 130

give the desired corrugated or undulating configuration to the center portion thereof, the sheet is necessarily considerably distorted. If the dotted lines 49^a (Fig. 9) represent the sheet of metal in its original form, the shape which it will assume after the pressing operation is over will approximate that indicated at 49^b in this figure. The pressing of the corrugations in the center portion of the plate to a certain extent thins out the metal at this place so that the finished panel will be thinner in the center than at its margins. To a greater extent, however, the dies draw into the corrugation metal taken from the edges or margins of the plate lying along parallel with the corrugations; the edges of the plate originally parallel to the lines of the intended corrugations being drawn in as indicated by the figure designated 49^b. This necessitates shearing the plate after it has been pressed along the dot and dash lines (Fig. 9). The panel is, of course, much stronger than if the additional surface required by the corrugations was obtained solely or very largely by a thinning of the metal. It has been found that the weakest points on the panel are near the ends of the corrugations. This is because the existence of the flat margins at the sides of the plate, that is, at the ends of the corrugations, prevent the adjacent portions of the top and bottom margins from pulling in to meet the requirement for additional metal. For this reason the corrugations instead of terminating abruptly are formed with the relatively long conical or semi-conical terminal points shown. If the only consideration were the maintenance of the corrugated portion of the panel at a thickness as near as possible to the original thickness of the plate, the corrugations might be tapered from their middle points to their terminations. However, this would decrease the value of the corrugations as beams besides leaving flat spaces of considerable area which would make the plate more susceptible to deflection and more easily punctured by a local thrust. The design I propose is a compromise between the two extremes. The main portion of the corrugations are of uniform depth and thickness, the inturned corrugations merging into the out-turned corrugations, which makes this portion of the structure essentially a series of beams, while the terminal portions of the corrugations are tapered down so as to di-

minish as far as possible the tendency to thin the sheet over much at these places.

The end shown in Fig. 8 is exactly like that shown in Figs. 4 to 7 inclusive, except that the panels designated 62, 63 are reversed so that the corrugations project outwardly from the marginal portions of the panels instead of inwardly, this necessitating, of course, the bending of the attaching flanges 64 in the opposite direction from that in which they are bent in the other construction. By forming the corrugations so that they lie substantially on one side of the plane of the marginal portion of the panels it is possible to make this reversal of the panels by simply reversing the bend of the attaching flanges (this being done, in any event, by an operation separate from the pressing of the corrugations), and thereby adapt the end to different conditions. For example, the Fig. 8 construction is desirable because the corrugations do not diminish the interior length of the car. On the other hand, in order to comply with the requirement of the Interstate Commerce Commission as to maintaining proper distance between the end ladder rungs and the pulling face of the coupler, it may be necessary to have the corrugations turned inwardly into the car as shown in Figs. 4, 5 and 6. The plates with the corrugations pressed in them in this manner may be kept in stock and flanged one way or another according to the conditions which prevail in the particular installation.

I claim:

The combination with the framing of a railway car, of a plate steel wall element formed with parallel stiffening corrugations of substantially the same width for the major portion of their length, and spaced one from another so that the stiffened portion of the plate presents a series of contiguous rib-like formations of substantially equal width which project alternately in opposite directions from each other, said corrugations extending across the plate and terminating within the edges thereof so as to leave flat margins for attachment to the car framing, the terminal portions of the corrugations being tapered in width and depth and merging into said flat margins.
